UNITED STATES PATENT OFFICE.

IRA A. WEAVER, OF SPRINGFIELD, ILLINOIS, ASSIGNOR TO THE WEAVER MFG. CO.,
OF SPRINGFIELD, ILLINOIS, A CORPORATION OF ILLINOIS.

JACK.

1,114,829.

Specification of Letters Patent.

Patented Oct. 27, 1914.

Application filed April 5, 1912. Serial No. 688,743.

To all whom it may concern:

Be it known that I, IRA A. WEAVER, a citizen of the United States, and resident of Springfield, in the county of Henry and 5 State of Illinois, have invented certain new and useful Improvements in Jacks, of which the following is a specification.

My invention relates to jacks and has particular reference to a novel twin jack 10 for use in connection with automobiles.

In the handling of automobiles either in public or private garages it frequently becomes necessary to elevate the wheels, axles or car body in order to facilitate repairs.

15 Furthermore, it is desirable, when the car is to remain out of use for any length of time, to relieve the tires of the weight of the car. This has heretofore been accomplished by the use of four independent jacks. When

20 it becomes necessary to make repairs to springs, axle or differential gearing, the car body must be supported in order to relieve the axles from such weight and permit the removal thereof if required. This has here-

25 tofore been accomplished by jacking up the car body, then replacing the jack with blocks or other supports. In such contingency, of course, the car must remain in that position until the repairs are effected and the parts

30 assembled. However, it often occurs that after the car is dismantled it is found that some broken part must be replaced and considerable time elapses before it can be secured. In such case the car must remain 35 where originally placed, oftentimes encumbering space which might otherwise be advantageously used.

I am aware that it is not broadly new to employ twin jacks mounted on a frame and 40 adapted for actuation from a single point. I believe, however, that the construction herein shown and described is novel in many particulars.

The advantages claimed for my construc- 45 tion are:

1st: The mounting of the twin jacks on a truck, the frame of the truck being triangular in outline. A particular advantage because of this construction is in that less 50 space is occupied, the device may be easily moved from place to place and the operating handle, later to be described, is so constructed that it swings into line with the frame and occupies very small space both in ship- 55 ping and storing.

2nd: The mounting of the twin jacks almost directly over two points of the triangular frame whereby a large proportion of the weight is carried by two of the wheels, the mounting being sufficiently inside of the triangle to obviate the possibility of tipping. 60

3rd: The provision of the unitary operating gear away from the center of the device. This is an important advantage inasmuch as if placed in the center it would very frequently interfere with the differential casing and be useless. 65

4th: The mounting of the operating handle at an angle and with freedom of movement through an arc of 180 degrees. With 70 this provision the jack may be operated without interference with springs, tail lights, trunk racks, or, in front, with fender or lamps.

5th: The provision in connection with the 75 unitary actuating gear of high and low speeds. The change in the speed is brought about merely by shifting the operating shaft and is advantageous in that the jacks may be raised quickly by the high gear into contact with the device to be lifted, then the gear shifted and the maximum lifting power secured; in connection with this gear I have provided an extensible handle whereby greater leverage may also be secured. 80

6th: The provision of a removable, adjustable cross-bar by means of which the posts of the jacks may be extended to contact the body of the car alone. In this construction the cross-bar is deflected at its 90 middle portion in order that it may escape interference with the differential casing or transmission shaft; furthermore, the posts referred to may be adjusted universally to meet different conditions. 95

Other advantages will appear hereinafter and be particularly pointed out in the claims.

My invention will be more particularly understood by reference to the accompanying drawings, wherein,

Figure 1 is a side elevation of a twin jack having the cross-bar and extensions applied thereto, the device being shown in co-operation with the body of an automobile; Fig. 105 2 is a plan view of the device with the cross-bar removed; Fig. 3 is an enlarged sectional view of the gearing showing the change speed construction; Fig. 4 is a detail on the line 4-4 of Fig. 3, showing the means for 110

retaining the beveled gear against bodily vertical movement; Fig. 5 is a sectional elevation of the novel crank employed in connection with my device, and Fig. 6 is a side elevation of one of the extensions secured to the cross-bar.

Referring more particularly to the drawings it will be seen that my novel jack is mounted on a triangular frame 10, having 10 bearings at the extreme ends in which swiveling casters 11, are mounted. The jacks themselves are mounted in rigid castings 12, forming a portion of the frame, the jacks being located inwardly from the casters. In such position it will be seen that 15 it will be practically impossible to tip the device when in service. The castings 12 are provided with hollow posts 13, having interior vertical slots 14 therein. At the 20 lower end as shown, only the portion of the post having the groove may be continued.

The upper end of the post 13, as shown in Fig. 4, is provided with a transverse extension or lip 15, adapted for coöperation with 25 a flange 16, carried by a beveled gear 17. This gear 17 is threaded and engages the threaded standard 18, which is the elevating device or jack. The weight carried by the standard is transferred to the casting 13, 30 through the beveled gear 17, and a series of ball bearings 19, running in races in the gear and in a hardened wearing plate 20, seated on the top of the post 13. At the lower end of the standard 18 I place a pin 35 21, coöperating with the slot 14 in the post. This is to prevent the rotation of the standard but permit its vertical movement. The upper end of the standard 18 has a suitable cap plate 22, riveted or otherwise secured 40 thereto. In order to assemble the parts just described, the ball bearings 19 are placed in the race on the plate 20, the gear 17 is tilted or rocked in such manner that the flange 16 may be entered under the lip 15, then the 45 standard 18 without the cap 22 is inserted from beneath, the gear rotated to elevate the standard until the pin 21 coöperates with the groove 14. The cap 22 may then be applied and thereafter the standard cannot be lowered far enough so that the pin 21 is free from the slot 14. Thus far the 50 description of the construction of the post, standard and beveled gear is identical in both of the jacks.

55 In suitable bearings 23 in the casting 12, is mounted a shaft 24. Secured to one end of the shaft, as shown in Fig. 1, is a beveled gear 25, meshing with the gear 17 and to the other end of the shaft are pinned or 60 keyed two gears 26—27. The gear 26 is in the form of a cylinder and is provided with gear teeth on the two faces, the teeth 28 meshing with the gear 17 and the teeth 29 meshing with a pinion 30, carried by an actuating stem 31. The gear 17 also keyed 65

to shaft 24, meshes with a gear 32, also carried by the stem 31. Neither of the gears 30—32 is permanently connected to the stem 31. However, each of the gears is provided with a radial slot 30a—32a and the stem with 70 a transverse pin 33, adapted for coöperation therewith. The parts are so arranged that by bodily shifting the stem longitudinally the pin 33 may be caused to engage with either of the gears 30—32. When in 75 engagement with the gear 32—which is the larger gear—motion will be transmitted to the shaft 24 through the gear 27, which is much smaller than the gear 32; thereby the motion will be multiplied. However, when 80 the stem is in engagement with the gear 30—which is small—motion will be transmitted to the shaft 24 through the large gear 26. Thus it will be seen that by a simple longitudinal movement of the stem the speed ratio 85 may be changed. The stem 31 and gear 32 are mounted in bearings in a casting 34, this casting also providing a bearing for the shaft 24 and being freely rotatable thereon to permit the shifting of the stem in an arc, 90 the shaft 24 being the pivotal point. If desired, the stem 31 may be mounted within a hollow casing or tube 35. To the upper end of the stem 31, as shown in Fig. 5, a crank 36 is pinned. This crank is hollow and 95 provides for a telescoping extension 37 carrying a handle 38. The extension is prevented from being pulled out of engagement with the crank 36 by means of a projection 39, in the form of a rivet. The extension is arranged to be removably held in a plurality of positions by means of a spring-pressed ball 40 held in a recess 41 in the crank 36, the ball coöperating with 100 spherical depressions 42 in the extension 37. By means of this extension crank, the leverage exerted by the operator may be increased for heavy loads or made short as desired.

As best shown in Fig. 1, I have provided 110 for coöperation with the body of a vehicle by means of jack standard extensions. These extensions 43 are provided with caps 44 on their upper ends and are held in a socket composed of two halves 45—46. The standard is merely guided in the socket 45, its vertical adjustment being accomplished by means of cotters 47, adapted to be seated in any of the apertures 48 in the standard. The two parts 45—46 are secured together 115 by means of a bolt 49, the contacting faces of the parts being toothed as at 50, whereby the part 45, carrying the extension 43, may be placed in any desired angular position. The part 46 is provided with a slot in which 120 is seated the connecting or cross-bar 51, and is adjustable lengthwise of the bar, being held in adjusted position by a set screw 52. The bar 51 is offset or deflected at 53 in order to permit of the operation 130

of the device without interference with the differential gear case. The bar is provided with clips 54, and set screws 55, by means of which the bar may be secured on the 5 caps 22 of the jacks. The cross-bar and extensions may be easily removed and the jacks caused to coöperate directly with the axles as required.

The particular advantage of the triangular frame and the swivel mounting of the 10 operating handle is in that the handle, as shown in dotted lines in Fig. 2 may be folded over onto the frame, thus making the whole device compact either in shipping or 15 when out of service in the garage. This function of rotatability of the operating handle is also of value in the garage, as the handle is normally down and out of the way and the car may be driven over the 20 jack.

Many of the expedients shown and described in connection with the device may be modified by skilled mechanics and such 25 modifications I consider to be within the scope of my invention.

I claim:

1. In a device of the class described, the combination of a triangular frame having swiveling caster supports at three points, 30 jacks mounted at two of the corners of said triangular frame, the caster supports contiguous to said jacks being extended outwardly beyond said frame, and a single operating means for both said jacks, said operating means being located at a point close to one of said jacks, substantially as described.

2. In a device of the class described, the combination of a movable frame having a 40 plurality of jacks mounted thereon, gearing whereby both said jacks may be operated simultaneously, said gearing being located at a point close to one of said jacks, and an operating shaft for said gearing, said 45 shaft being angularly mounted and extending to a point substantially midway between the two jacks, substantially as described.

3. In a device of the class described, the combination of a movable frame having a 50 plurality of jacks mounted thereon, gearing whereby both said jacks may be operated simultaneously, said gearing being located at a point close to one of said jacks, and an

operating shaft for said gearing, said shaft being angularly mounted and movable in 55 the arc of a circle about a pivot at the point of connection to the gearing, substantially as described.

4. In a device of the class described, the combination of a triangular frame, jacks 60 mounted on said frame, means for operating said jacks from a single point, an operating shaft mounted at an angle and adapted to be swung about a pivot close to one of said jacks, whereby said operating shaft may be 65 swung into line with one of the members of said frame, substantially as described.

5. In a device of the class described, the combination of a frame, a plurality of jacks mounted on said frame, means for actuating 70 said jacks, said actuating means including a longitudinally movable stem, an operating crank and a plurality of gears, the parts being arranged whereby the speed of operation of said jacks may be changed relative 75 to the speed of the actuating means by the shifting of said stem, substantially as described.

6. In a device of the class described, the combination of a triangular frame, jacks 80 mounted at two corners of said frame, a unitary operating means for both jacks, the operating rod being projected from said frame at an angle and having the capacity of rotation about the jack operating shaft 85 as an axis, the operating rod when in one position lying substantially in line with one member of the triangular frame, substantially as described.

7. In a device of the class described, the 90 combination of a frame, a jack carried thereby, said jack including a threaded standard and a gear meshing therewith, said gear being provided with a continuous, inwardly extending flange, and a lip on said frame 95 projecting outwardly therefrom, said lip being adapted to coöperate with the flange on the gear to prevent the disengagement of the gear from the frame while in mesh with said threaded standard, substantially as de- 100 scribed.
